To all whom it may concern:

Be it known that I, EVERETT IRVING ROGERS, Jr., a citizen of the United States, residing at 7 Beverly Street, Providence, in the county of Providence and State of Rhode Island, have invented a new, original, and ornamental Design for a Jewelry-Display Container, of which the following is a specification, reference being had to the accompanying drawing, forming part thereof.

Drawings:

Figure 1 is a side view of a jewelry display container showing my improved design.

Figure 2 is a top plan view of the same. The article shown is in the form of a container body in which the shank of the button forms a handle for the cover. The cover is transparent, being constructed preferably of glass, articles within the container being thereby exposed to heighten the ornamental effect.

I claim:
